UNITED STATES PATENT OFFICE

2,542,732

DEVICE FOR CONVERSION OF FREQUENCIES

Emile Torcheux, Paris, France, assignor to Societe Francaise Radio Electrique, a corporation of France

Application May 3, 1945, Serial No. 591,714
In France January 26, 1940Section 1, Public Law 690, August 8, 1946
Patent expires January 26, 1960

4 Claims. (Cl. 250—40)

1

This invention relates to devices for conversion of frequencies such as those used in the transmission or reception of radio-electric waves.

The construction of transmitting and receiving apparatus capable of operating on any frequencies over their entire range under conditions of great stability and precision of adjustment of the wave transmitted or received is of great interest not only with respect to the reliability of the communication but also as to the quality of reception and rapidity of establishing a connection. These conditions are of particular importance in communications in which the wave lengths used are frequently changed and where it is desired to tune to a predetermined wavelength and establish immediate contact with the best possible ratio of signal to parasitic noise. In this connection it may be remarked that an apparatus as visualised in the present invention must be capable of being regulated in advance on to a given wavelength and be capable of at once receiving an emission having this wavelength; the reception must take place under the best conditions of the ratio between useful signal to parasite noises, that is to say, the receiver must be exactly regulated to the wavelength to be received.

In most cases, the precision and stability are expressed as a percentage of the frequency transmitted. Means are known for obtaining very great stability in the case of a particular frequency or in the vicinity of this frequency, but there is then excluded the possibility of varying the frequency over a continuous and extended range.

Now what it is required to obtain is that with the same system of communication, whether this be in short waves or medium waves, the band occupied presents the same absolute value; for example, in telephony a value of 6 kc. and in telegraphy a value limited by the speed of manipulation.

The device forming the object of the present invention enables transmitters and receivers to be produced having the above qualities for any frequency within the entire range for which the transmitter or receiver is constructed.

This device applied to a receiver serves to bring the various frequencies F_1 of an extended range into closer limits of a lower range of frequencies F_0 covered in a continuous manner by a tuning system with linear variation of frequency; applied to a transmitter, it serves on the contrary to bring the various frequencies F_0 of a restricted range into more extended limits of a higher

2

range of frequencies F_1 . The device acts on the well known principle of the change of frequency and makes use of members and devices known per se as hereinafter indicated, the invention consisting essentially of the combination of three elements as follows:

1. At least one frequency changer selector comprising, as known per se, at least one filter capable of being tuned to the frequencies F_1 by a tuning system with linear variation of frequency.

2. At least one generator to produce, in a manner known per se, at least two substitutable fixed frequencies F_0 selected in such a manner that in the frequency changer the equation:

$$|F_1 - F_0| = F_0$$

can be satisfied by using one of the frequencies F_0 whatever may be the value of F_1 under consideration.

3. A system of connection ensuring a demultiplication of movement between the member controlling the tuning system on the frequencies F_0 and the member controlling the tuning system on the frequencies F_1 , in such a manner that there corresponds to every variation of frequency on the frequencies F_0 the same variation in absolute value on the frequencies F_1 , the said system of connection comprising furthermore a displacement device effective to modify, independently of the movement of the member controlling the tuning system on the frequencies F_0 and conjointly with the placing in service of the fixed frequency F_0 utilised in the change of frequency, the member controlling the tuning system on the frequencies F_1 to a position of adjustment; this movement, defined by the displacement effected by the member controlling the tuning system on the frequencies F_1 from its initial position (i. e. that from which the frequencies F_1 are traversed) to its position of adjustment, being such that when the tuning system on the frequencies F_1 is tuned to the frequency corresponding to the said position of adjustment, the system of tuning on the frequencies F_0 is tuned to one of the limit frequencies of the range of frequencies F_0 .

The invention will now be further described with reference to the Figure 1a of the accompanying drawings, in which the device according to the invention is represented diagrammatically as applied by way of example to a receiver and as comprising only one frequency changer stage. In such a device it is a question of bringing the frequencies F_1 of a wide range extending from F_1^0 to F_1^1 into the narrower limits F_0^0 , F_0^1 of a

lower range of frequencies F_0 covered in a continuous manner by a tuning system with linear variation of frequency. This tuning system, represented by C_0 , has for its object to select the frequency F_0 in the frequency selector S_0 , and it is controlled by an actuating member U_0 the displacement a_0 of which is connected to the frequency F_0 by the linear rule:

$$a_0 = K_0 F_0 + \beta_0 \quad (1)$$

in which K_0 and β_0 are constants.

The device comprises in combination, in accordance with the foregoing general statement of invention:

1. A frequency changer selector ($S_1 - M_1$) comprising at least one filter adapted to be tuned on the frequencies F_1 by a tuning system with linear variation of frequency. This tuning system, represented by C_1 on Figure 1a, is controlled by a controlling member U_1 the displacement a_1 of which is connected to the frequency F_1 by the linear rule:

$$a_1 = K_1 F_1 + \beta_1 \quad (2)$$

in which K_1 and β_1 are constants.

2. A generator G producing at least two substitutable fixed frequencies. These fixed frequencies, any one of which will be indicated by F_q , are selected in such a manner that in the frequency changer M_1 the equation:

$$|F_1 - F_q| = F_0 \quad (3)$$

may be satisfied by using one of the frequencies F_q , whatever may be the value of F_1 under consideration.

The Equation 3 may be set out in the following algebraical form:

$$F_1 - F_q = \epsilon F_0 \quad (3')$$

by assuming that:

$$\epsilon = +1 \text{ when } F_1 > F_q$$

and

$$\epsilon = -1 \text{ when } F_1 < F_q \quad (4)$$

The fixed frequencies will be obtained, for example, by means of one or more quartz oscillators in order to ensure a great stability of frequency.

3. A system of connection L ensuring a demultiplication of movement as between the control member U_0 of the tuning system C_0 and the control member U_1 of the tuning system C_1 , in such a manner that there corresponds to every variation of frequency on the frequencies F_0 the same variation in absolute value on the frequencies F_1 . It is thus necessary to have:

$$dF_1 = \epsilon dF_0 \quad (5)$$

The value of ϵ is given by the Equation 4 since the Equation 3' must be satisfied at the same time as Equation 5.

Let us indicate by m the ratio of demultiplication between the respective displacements d_{a_0} and d_{a_1} of U_0 and U_1 , there is given:

$$d_{a_1} = m \cdot d_{a_0} \quad (6)$$

From the Equations 1, 2, 5 and 6, there is deduced the value of m as follows:

$$m = \epsilon \frac{K_1}{K_0} \quad (7)$$

The system of connection L comprises, inter alia, a displacement device D effective to modify the adjustment of U_1 independently of the movement of U_0 . This adjustment is defined by the displacement necessary to cause a_1 to pass from its initial value a_1^0 corresponding to the initial

70
75

4

frequency F_1' from which the range of frequencies F_1 is passed through, to its adjustment value a_1^* to which the frequency F_1^* corresponds. There is thus obtained by definition of the adjustment:

$$\gamma = a_1^* - a_1^0$$

with, according to the Equation 2,

$$a_1^* = k_1 F_1^* + \beta_1 \quad 10 \text{ and}$$

$$a_1^0 = K_1 F_1' + \beta_1$$

There is thus obtained:

$$\gamma = k_1 (F_1^* - F_1') \quad (8)$$

Owing to the existence of the system of connection when the tuning system C_1 is regulated to the frequency F_1 , the tuning system C_0 is regulated to a frequency F_0^* such that the Equation 3' is satisfied. There is thus obtained:

$$F_1^* - F_q = \epsilon F_0^* \quad (3'')$$

Taking this equation into consideration (8) becomes:

$$\gamma = K_1 (F_q - F_1' + \epsilon F_0^*) \quad (8'')$$

in which according to the invention, F_0 is equal to one of the limit frequencies of the range of frequencies F_0 , that is to say either to F_0^0 or F_0^1 .

This relation permits of determining γ as soon as the direction has been fixed in which the frequencies F_1 are passed through. If, for example, the direction is of increasing frequencies, on the one hand $F_1' = F_1^0$ and on the other hand if the lower limit F_0^0 be taken for F_0^* , the frequencies F_0 can only increase, that is to say, there is given: $\epsilon = +1$ according to the Equation (5): on the contrary, if the upper limit F_0^1 is taken for F_0^* , the frequencies F_0 can only decrease that is to say, there is given: $\epsilon = -1$. There are consequently only two possible solutions, for with

$$\epsilon = +1, \gamma (\epsilon = +1) = K_1 (F_q - F_1^0 + F_0^0) \quad (8'')$$

and with

$$\epsilon = -1, \gamma (\epsilon = -1) = k_1 (F_q - F_1^0 - F_0^1) \quad (8''')$$

45 The device according to the invention permits of obtaining simultaneously the precise tuning of the two selectors S_0 and S_1 at the same time that it permits of covering extensive ranges with very few electric contacts, due to the fact that 50 the passage from one section of frequencies to the following one takes place by changing the zone used of the control member of the tuning system. This reduction in the number of the electric contacts is still further accentuated when 55 there are placed in cascade several similar devices. On the other hand, the device is particularly well adapted for the use of the two frequencies which can be obtained in the change of frequency (these two frequencies are given by the Equation 3' according to the value of ϵ).

In this case, it is obviously necessary to provide means for reversing the ratio of demultiplication between the members U_0 and U_1 . These means may consist of mechanical devices such as connecting rods or eccentrics or electrical devices such as condensers with two symmetrical stators with commutation or a set of two similar condensers of connected and reversed movement, with commutation.

The system of connection is carried out by means of a train of gearing with differential movement permitting, by displacement of the crown wheel of the gear carrying the satellites, of shifting the control member U_1 with respect to the control member U_0 without modifying the

5

ratio of demultiplication between these two members.

An advantageous arrangement is realisable when the range of frequencies F_0 covers the frequencies f to $3f$ (f being a definite number of kilocycles) and the range of frequencies F_1 covers the frequencies from $3f$ to $9f$. Thus in this case, with two fixed frequencies only, equal respectively to $5f$ and $7f$, all the frequencies F_1 can be brought into the range of frequencies F_0 by using as the connecting system a system of gearing with differential movement having a ratio of $1/3$ and comprising four positions of adjustment.

In general, the range to be transposed is very extended, it is then transposed by successive stages by the aid of devices similar to that described, placed in cascade. In this the ranges to be transposed is decomposed into intermediate ranges of decreasing extent in such a manner as to terminate finally at the range of frequencies F_0 . It is later on indicated, by way of example, how it is possible to rise from the range of frequencies F_0 to a range of frequencies F_n of any rank by employing the decomposition termed with base 3. In case of the reception, the frequencies F_0 varying from f to $3f$ arise from a first frequency change selector receiving the frequencies F_1 variable from $3f$ to $9f$ and operating with two substitutable fixed frequencies $5f$ and $7f$, the frequencies F_1 arising themselves from a second frequency changer selector receiving the frequencies F_2 variable from 3^2f to $3^{(2+1)}f$ and operating with two substitutable fixed frequencies $5 \times 3^{(2-1)}f$ and $7 \times 3^{(2-1)}f$, the frequencies F_2 from a third frequency changer selector receiving the frequencies F_3 variable from 3^3 to $3^{(3+1)}f$ and operating with two substitutable fixed frequencies $5 \times 3^{(3-1)}f$ and $7 \times 3^{(3-1)}f$, and so on, the frequencies F_{n-1} variable from $3^{n-1}f$ to $3^{n-1+1}f$ arising from an n th frequency change selector receiving the frequencies F_n variable from $3^n f$ to $3^{(n+1)}f$ and operating with two substitutable fixed frequencies $5 \times 3^{n-1}f$ and $7 \times 3^{n-1}f$.

The base 3 is particularly advantageous because on the one hand it allows the simplification of the mechanism and on the other it ensures protection against image waves, against the waves having the value of the frequencies resulting from the successive transpositions and against the reinjection of the heterodyne in the aerial.

Other distributions of the intermediate ranges are, however, possible. For example, the frequencies F_0 still extending from f to $3f$, the first frequency change selector covers the frequencies from $4f$ to $12f$ and operates with two fixed frequencies $7f$ and $9f$, the second frequency change selector covers the frequencies from $16f$ to $48f$ and operates with two fixed frequencies $28f$ and $36f$, the third frequency change selector covers the frequencies from $64f$ to $192f$ and operates with the fixed frequencies 112 and $144f$, and so on.

It would also be possible to start from a different range F_0 extending, for example, from $2f$ to $4f$. There might then be used a first selector covering the frequencies from $12f$ to $24f$ and operating with the substitutable fixed frequencies $16f$, $18f$ and $20f$, a second frequency change selector covering the frequencies from $72f$ to $144f$ and operating with the substitutable fixed frequencies $96f$, $108f$ and $120f$, and so on.

When the receiver operates on the heterodyne

6

principle, the frequencies F_0 are themselves made to beat with the variable frequency of the heterodyne, according to known practice. Where the frequencies F_0 extend from f to $3f$, there is used a heterodyne giving the frequencies from $3/2f$ to $5/2f$, in such a manner as to bring all the frequencies F_0 to the frequency $f/2$ of the stage of mean frequency.

By placing in service successively all the frequency changer selectors, it would be possible to successively cover the range of frequencies F_1 , the range of frequencies F_2 , the range of frequencies F_3 , etc. As the frequencies F_0 can also be received directly, it will be seen that there can be covered in this way a very extended range starting from the smallest value of F_0 and extending up to the greatest value of F_n .

An indicator device of the frequency F_n , on which the apparatus is regulated, is actuated on the one hand, from the shaft U (see Figure 1a) ensuring the simultaneous drive of the driving members U_0 U_1 , U_2 . . . U_n and on the other hand, from the section handle T (or combiner) operating conjointly the regulation of the displacement device or devices and the placing into service of the fixed frequency or frequencies.

By reason of the linearity of frequency of the tuning systems, the indicator device indicates in a general way angles proportional to the frequencies. It may, therefore, take the form of a revolution counter the unit column of which is driven from the tuning knob (controlling the shaft U) and the hundreds or tens column by the combiner, if necessary through the intermediary of a system of differential gears. The possibility is thus given of obtaining directly the indication of the frequency in kilocycles and covering the whole range dealt with by the aid of two means of control only, the tuning knob and the combiner.

Naturally, the device applies equally to emission as to reception, it is sufficient, according to known practice, to change the direction of amplification and to consider as transmitted wave, the wave previously considered as received wave.

There will now be described, with reference to the accompanying drawings and by way of example only, one method of carrying out the above-described system, and in the description of this method, there will be indicated various constructional forms for certain of the members or elements entering into the constitution of the system.

In the drawings referred to,

Figure 1 shows the wiring schematic of part of a receiver according to the invention.

Figure 1a shows a simplified diagram of the essential parts of the embodiment of the invention.

Fig. 2 is a perspective view of part of the operating mechanism indicated diagrammatically in Fig. 1;

Figs. 3 and 4 are diagrammatic side elevations of parts of Fig. 2 in different operative positions;

Fig. 5 shows a general view of the mechanism of one embodiment of the invention;

Figs. 6 and 7 show diagrammatically how to divide and operate an embodiment of the invention shown by way of example;

Figs. 8 and 9 show in perspective and partly diagrammatically some further mechanical details and associated wiring schematics; and

Fig. 10 shows a perspective view of a coordinating mechanism for operating a device according to the invention.

The receiver according to the invention shown in Fig. 1 comprises the following elements:

(i) A first filter changer block 4 of range comprised between the limits 250-750 kilocycles, having two pre-selector circuits 2 and 3, an amplifier valve 4, a tuned circuit 5 and a mixer valve 6;

(ii) A heterodyne 7 of range 375-625 kilocycles, as stable as possible in comparison with the temperature and controlled mechanically with precision; this heterodyne excites the modulator electrode of the valve 6 of the preceding block, in such manner that at the outlet of this block there is collected a fixed frequency or very stable mean frequency of 125 kc.;

(iii) A mean frequency block 8 comprising (a) a narrow pass-band filter 9 regulated to allow the passage simply of the frequency 125 kilocycles and the immediately adjacent frequencies with variable selectivity and (b) a mean frequency amplifier with two valves 10 and a beat mixer 11;

(iv) A mean frequency heterodyne 12 of 127 kilocycles, and

(v) An anti-fading detector block 13 and low frequency amplifier.

This combination of elements, acted upon by an aerial 14, in the first position of a commutator 15, ensures the reception of the first sub-range comprising the frequencies from 250 to 750 kilocycles.

A second sub-range of 750 to 2500 kilocycles is received by the addition to the preceding elements of:

A second filter-changer block 16 comprising two pre-selector circuits 17 and 18, an amplifier valve 19, two circuits 20 and a mixer valve 21;

A heterodyne 22 of the two fixed frequencies 1250 and 1750 kilocycles produced by quartz oscillators, with a commutator 23, for placing into operation the one or the other frequency.

The total extent of the range, from 250 to 2500 kilocycles, is divided into 9 equal sections, each extending over 250 kilocycles as shown in the table below, the said table supplying in a general way the essential indications as to the positions and the manipulations of the members (adjustment of the condensers of selector circuits and heterodyne, direction of rotation of the said condensers, quartz oscillator used on the heterodyne) corresponding to each of the said sections.

Direction table per section

Of the above values, (1) is controlled by the members of the 1st differential, (2) and (3) are controlled by the members of the direction reverser, (4) is controlled by the members of the 2nd differential, (5) is controlled by the members of the quartz reverser and (6) is controlled by the members of the aerial tapping.

Detailed examination of the above table shows

different arrangements characteristic of the system. Thus, for the section 250-500 the first high frequency block is utilised in the extent of this sub-range, the displacement or adjustment of the condensers of the selector circuits is zero, the direction of the said condensers is forward, the direction of rotation of the condenser of the heterodyne associated with the first block (heterodyne 7) is also forward, the second high frequency block is not in operation and the position of the aerial commutator 15 is such that the aerial is tapped at the inlet terminals of the first high frequency block.

In the case of the section 500-750, there are the same arrangements except that the zone of utilisation of the first block HF is that of 500 to 750 kilocycles, the filter condensers being displaced by 90°.

For the section 750-1000 the 1st block HF is utilised in its 250-500 range (traversed in the descending direction 500-250) the filter condensers being displaced by 90°, their direction of rotation, as also that of the heterodyne condenser, being in the reverse sense, the 2nd block HF is utilised in its range 750-1000, the filter condensers being displaced by -25° 7, their direction is forward, the quartz oscillator in use in the heterodyne 22 is that of 1250 kilocycles and the aerial is connected, through the commutator 15, at the input of the 1st block HF.

The data of the table, for the other sections, will be self-evident in the light of the above explanations.

The manipulation of the different members is ensured by means of two handles, one controlling in integral rotation (single control) the movement of the unit drum of the indicator-counter of the frequency and the movement of the condensers of heterodyne 7 and of the filter changer blocks 1 and 16, the other, the displacements of the heterodyne condensers and blocks, the reversals of running of the condensers, the quartz oscillator and aerial commutators, the numeral drums of the frequency indicator-counter and all manipulations appertaining to the passage from one section to another. Of these handles, the first has a continuous movement and the second has an interrupted movement and can fix itself on nine different positions (one per section).

The two categories of controls to which respectively the two handles are allocated, are indicated in a general way on Figure 1, the first by dotted lines 23 and the second by broken lines 24.

The interrupted control handle (or combiner) firstly drives directly the tens of kilocycles wheel of the counter through the intermediary of a differential at the rate of two and a half revolutions

per section; secondly, acts on the adjustment of the condensers of the 1st and 2nd filter changer block effected by the single control, according to the above table, these adjustments being effected by the displacement of the connecting members of the differentials 25 and 26; thirdly, actuates the direction reversers of the condensers of the filter changer blocks 1 and 16; fourthly, actuates the reversers of the quartz oscillator of the heterodyne 22; and fifthly manipulates the aerial commutator 15.

These multiple operations are ensured by the intermediary of a drum selector, illustrated in Figure 2.

As shown in this figure, the selector comprises a drum 30 provided with indentations of different depths or widths into which penetrate the noses of a number of levers or pawls 31, 32, 33, 34. Each of these levers actuates a rod system 35, 36, 37, 38. The rod systems 35, 36 act on the differentials 25, 26 to effect the adjustment of the variable condensers of the filters. The rod systems 37, 38 cause the movement of the aerial commutation members, of the quartz oscillators and of the reversal of the filter condensers.

The drum 30 is actuated, through an operating spindle 39, by a Maltese cross drive 40 and a set of gears 41 having a ratio of 1:2.25, in such a manner that there corresponds to each rotation of the spindle 39 $1\frac{1}{9}$ of a revolution of the drum 30. Keyed onto the spindle 39 is a cam 42 operating a lever 43 provided with a rod or pawl 44. The function of the rod or pawl 44 is to set the levers or pawls 31 to 34 so as to permit the rotation of the drum 30 towards its new position. The lever 43 also drives a rod system 45, the function of which is to lock the adjustable members of the differentials when they have been brought into their approximate position by the rod systems 35, 36.

Furthermore, by means of a retarding member (which may for example, be of the clockwork or dash-pot type) the pawl 44 is kept for a suitable time in the set position, after the return of the cam 42. This permits of avoiding the manipulation of the members for all the intermediate positions between two non-adjacent sections.

Thus, when the section is changed, the manipulations are as follows: 1st, the unlocking of the differentials; 2nd, setting of the levers or pawls; 3rd, rotation of the drum; 4th, freeing of the pawls; 5th, locking of the differentials.

Figures 3 and 4 show in plan view the position of the parts shown in Figure 2 in the phase of rotation of the drum (Figure 3) and in the phase of operation of the receiver (Figure 4).

Figure 5 illustrates a conventional representation of the entirety of the elements of the mechanical controls of the system.

Figure 5 shows the selector drum 30 operated through the spindle 39 by the Maltese cross 40, the cam 42, the pawls or catches 31, the lever 43 and the rod or pawl 44. Connected to the locking rod system 45 are a retarding device 46 constituted by a dash-pot, a resetting spring 47, locking pieces 48, 49 constituted by levers hinged at one of their extremities to the rod 45 and carrying at the other extremity rollers 50, 51 engaging in notches 52, 53, 54, 55 on the adjustable elements of the differentials 26, 25, through the intermediary of which are driven the variable condensers 58, 59 of the filters of the frequency selector-changer blocks 1 and 16.

The lever or pawl 31 is connected to the rod 35, which in turn operates, through a toothed 75

sector 60, the displacement of the differential 25 driving the variable condensers 59 of the first filter changer block 1. A re-setting spring 61 draws the lever or pawl towards the drum. A similar operating movement is constituted by the rod 36, actuated by the lever or pawl 32 (not shown in Figure 5), which operates through the differential 26 and a sector 62 and against the action of a spring 63, the displacement manipulation of the condensers 58 of the second filter changer block 16.

The commutation rod system 37 effects either the reversal of direction of rotation or the reversal of variation of the capacities for the same direction of rotation of the variable condensers of the heterodyne 7 and of the filter block 1. This result is obtained by the play of two commutators 64 and 65 putting into operation one or the other of two symmetrical stators with which these condensers are provided. A spring 66 draws the rod 37 back to starting position.

By means of a similar mechanism the rod 38 actuates the commutator 23 of the quartz oscillators Q_1 and Q_2 of the heterodyne 22 and the rod 67 the commutator 15 of the aerial 14.

There will now be described the detail of the connections operating the continuous movement control. The spindle 68 of this control, upon which is keyed a handwheel 69, drives by a helicoidal worm 70 an intermediate spindle 71 which, by means of a tangent worm 72, drives the spindle 73 of a variable condenser 74 of the heterodyne 7. There is also keyed on the spindle 68 a pinion 75 which, through a train of toothed wheels 76, 77, 78, drives the elements of the differentials 26, 25 with which there are integral in rotation the filter condensers 58, 59.

The spindle 71, through the gears 76', 77', 78', drives the drum 79 (unit drum) of a drum counter 80. To obtain a transmission without play, the intermediate gear 77' is applied against the other gears by means of a compensator spring 88.

The ratios of reduction of these different controls are as follows: for a half turn of the variable condenser 74 of the heterodyne 7, the condensers 59 of the first filter changer block 1 rotate by $\frac{1}{4}$ of a revolution, those of the second block 16 rotate by $\frac{1}{14}$ of a revolution and the drum 79 of the units of the frequency indicator-counter rotates by 25 revolutions.

The ratio of reduction between the movement of the condensers 59 and 58 as also the angles of fixation of the latter condenser, may be easily deduced from the general formulae given at the beginning of the description.

Actually, the condenser 58 is supposed to cover in one-half revolution the frequencies from 750 kc. to 2500 kc. There is thus obtained: for

$$\alpha_1 = 0 \dots F_1^0 = 750$$

and for

$$\alpha_1 = \pi \dots F_1^0 = 2500$$

65 These two particular values applied to the Equation 2 give for k_1 the value:

$$k_1 = \frac{\pi}{1,750} \quad (9)$$

70 In the same way, the condenser 59 is supposed to cover in one-half revolution the frequencies from 250 kc. to 750 kc., whence there is obtained: for

$$\alpha_0 = 0 \dots F_0^0 = 250$$

for

$$\alpha_0 = \pi \dots F_0^4 = 750$$

whence according to the Equation 1

$$k_0 = \frac{\pi}{500} \quad (10)$$

the ratio of reduction m given for the Formula 7 is thus:

$$m = \epsilon \cdot \frac{500}{1750} = \epsilon \frac{2}{7}$$

Referring to the Equation 4 and to the table previously given, it will be seen that there is for lines 3, 4, 5 of this table $\epsilon = -1$, that is to say, the reverse direction, as indicated, whilst for the four last lines there is given $\epsilon = +1$, that is to say, the forward direction.

For the value of the positions of adjustment, it is thus necessary to use the Formula 8''' for the lines 3 to 5 and the Formula 8'' for the four last lines. There are thus found the values indicated in the table:

For the third line:

$$\gamma = \frac{\pi}{1750} (1250 - 750 - 750)$$

$$= \frac{\pi}{1750} \times -250 = -\frac{\pi}{7} = 25^\circ, 7$$

For the fourth and fifth lines:

$$\gamma = \frac{\pi}{1750} (1750 - 750 - 750) = \frac{\pi}{1750} \times 250 = \frac{\pi}{7} = +25^\circ, 7$$

For the sixth and seventh lines:

$$\gamma = \frac{\pi}{1750} (1250 - 750 + 250) = \frac{\pi}{1750} \times 750 = \frac{3\pi}{7} = +77^\circ$$

For the two last lines:

$$\gamma = \frac{\pi}{1750} (1750 - 750 + 250) = \frac{\pi}{1750} \times 1250 = \frac{5\pi}{7} = 128^\circ, 5$$

In the counter 80, between the drum 81 of the tens and the drum 79 of the units, there is interposed, in addition to the normal connection mechanism from drum to drum according to the counter or meter system, a connection through a differential 82, permitting of effecting a displacement corresponding to two and a half revolutions for each change of section (corresponding to 250 kilocycles). The displacement of the differential 82, starting with the movement of the primary spindle 39 of the interrupted control, is transmitted by spindles 83, 84 and toothed wheels 85, 86 and 87.

As regards the heterodyne block 7, all useful constructional precautions should be taken to ensure its accuracy; in particular the variable condenser, the self-inductance and the bulb of the oscillator valve, should or may be mounted in a copper box forming an hermetic seal, which box itself may be mounted on the front panel of the receiver. To ensure the greatest possible constancy with reference to the temperature, the variable condenser should or may be constructed of metal, the coefficient of expansion of which varies very little as a function of the temperature. Even then, the frequency is not rendered entirely independent of temperature; there is still a separation, which, however, can be reduced by about 70% by using condensers having a negative temperature coefficient, which annuls the separation in the centre of the range in question. In place of such compensation, there may be utilised two bimetallic strips 89, 90 as reading index, one of

these strips being utilised for running in one direction and the other for running in the opposite direction.

The means employed to obtain the reversal of the relative direction of variation of the capacity of the condensers (that is to say, the condensers of the precision heterodyne 7 and condensers of the filter 1) for the same direction of rotation of the rotors, consists in utilising condensers of the type with two symmetrical stators, placed in use alternately and automatically by the action of the commutators 65, 66.

These condensers are, furthermore, of a type with linear variation of frequency; preferably, there will be provided for the condenser of the precision heterodyne 7, the kind of condenser of this type in which the desired linear law of variation results from the profile of the blades, and for the condensers of the filter 1, those of the kind in which the desired linear law is obtained by the interposing of a cam of suitable profile between the actuating spindle and the spindle of the rotor of the said condenser. This system permits of obtaining, with the desired linear law, a more extended ratio between the maximum frequency and the minimum frequency, an extension necessitated by the development of range of the filter 1.

While the basic principles of the invention in its widest scope have been clearly set forth in the preceding description, it remains to describe briefly, as illustrated in Figures 6-10, certain arrangements which will aid in understanding the application of the invention to a very wide range of frequencies and which will enable an easier manipulation of the control in the wide system, which latter can make use of servo-motors.

The invention may be carried into effect in various ways.

One embodiment will be hereinafter described, by way of non-restrictive example, as applied to the construction of a receiver, said embodiment including numerical values in order that the example may be fully illustrative.

In a general way, in apparatuses of the type in question in this invention, the reading of the frequency takes place on a cyclometer counter, the total range of the apparatus being divided into "sections," each covering the same number of kilocycles, and a direct variation of frequency of the resonant circuits being maintained proportionately to the variation of position of the control member.

The frequency is determined by means of two manipulations. The first enables the selection of the section containing the frequency to be received; it actuates the elements of the counter indicating the number of hundreds of kilocycles and a set of combining members which prepares the necessary combinations. The latter are executed when the selected section is engaged.

The second manipulation serves to travel over the "section"; it therefore controls the variable frequency heterodyne of the last change of frequency and operates, in the counter, the wheels of the tens and of the units.

Assume a total range of from 100 to 24,300 kilocycles, this range being divided into sections of 100 kc.

The high frequency portion comprises (Figure 6) five blocks I, II, III, IV, V of identical design, differing only by their range of frequency. They are used in progression according to the frequency to be received.

For the lowest frequencies (100-300 kc.) only

block I is used; this block in conjunction with a variable heterodyne H supplies to the amplifier MF the oscillations having a mean frequency of 50 kc., which supply the amplifier detector BF; for higher frequencies (300-900 kc.) blocks I and II are utilised.

The block II transposes the frequency which it receives by utilising quartz oscillators and delivers under these conditions at its output, when the signal frequency varies, a variable intermediate frequency which covers the range of the block I.

The receiver then behaves as a receiver with double frequency change, the first mean frequency of which is variable and the second is fixed.

For still higher frequencies (900-2700 kc.) block III comes into operation and, by the same procedure, supplies a variable intermediate frequency covering the range of the block II. The receiver is then of triple frequency change.

The reception of still higher frequencies necessitates the placing into service of supplementary blocks IV, V, in the example shown.

The following table shows the ranges corresponding to the placing in series of the different blocks:

Table

Wave to be received		Intake from aerial	High frequency blocks used	No. of "sections" of 100 kc.
F., kcs.	Meters			
100- 300	3,000-1,000	Block I	I	2
300- 900	1,000- 333	Block II	I, II	6
900- 2,700	333- 111	Block III	I, II, III	18
2,700- 8,100	111- 37	Block IV	I, II, III, IV	54
8,100-24,300	37- 12.4	Block V	I, II, III, IV, V	162

Each high frequency block comprises three tuned circuits of variable frequency covering a range of ratio 3, an amplifier valve and a mixer valve.

The following component members are utilized.

1. Reduction and adjustment

The condensers of direct variation of frequency are controlled from a single manipulation (manipulation of the variable heterodyne condenser) in such a manner that the condensers appertaining to a block of higher index move three times as slow as the condensers of the block of lower index immediately adjacent.

On the other hand, according to the sub-range selected, the adjustment of the condensers of one block with respect to those of the block immediately adjacent must have a well defined value.

These two conditions are obtained by differentials, which are inserted between the controls of the different blocks according to the diagrammatic arrangement of Figure 7, which is self-explanatory. The adjustment takes place by putting into a definite position the satellite-carrying crown of the differential. According to the present invention, this operation is carried out by a small servo-motor rotating automatically just the amount necessary to bring the crown to the desired adjustment, see Fig. 9.

The said mechanism comprises a differential 101, having a reduction ratio of 1:3, coupling the shaft 102 of the lower block with the shaft 103 of the upper block, the crown of the differential being marked 104 and the satellites carried thereon 105. The crown 104 is in engagement with a

servo-motor 106 and it is integral with a contact disc formed in two parts 107, 107' with a slot 108 between the parts. Brushes 109, 109', 109'' etc., bear on the contact disc. The motor 106 is supplied with electric current from a source 110 (Figure 9b), indicated by its two poles + and -. The terminals of the motor are connected respectively to the brushes 109''' and 109''', and, through resistances 111, 112, to one of the poles of the source 110. The other pole of the source 110 is connected to the brushes 109, 109' and 109'' through contacts 113, 113', and 113'', of the section combine. The making of one of these contacts, for example the contact 113'', causes the setting in rotation of the motor in the desired direction, the rotation of the motor continuing until the slot 108 comes opposite the brush 109''. At this moment, the motor stops, the crown having undergone a displacement equal to the angular distance between the brushes 109', 109''. The closing of the contact 113 would have caused the placing in rotation of the motor in the opposite direction until the arrival of the slot 108 opposite the brush 109.

There is thus obtained, by a simple electrical control, the displacement of the differentials, the

manipulation of the section combiner being limited to effecting contacts, with consequent elimination of the mechanical efforts necessitated by a direct control.

2. Reversal of direction

45 To obtain maximum efficiency in the use of the apparatus, it is necessary to utilise in the successive changes of frequency, sometimes the upper beat and sometimes the lower beat. It is thus necessary that the variation of the capacity of 50 certain blocks should be an increase for certain sections and a decrease for others. This result is obtained by providing, on each block, not simply a single set of condensers but two sets controlled in opposite directions and by selecting, according to the section, that one of the two which is suitable.

55 Such an arrangement is obtained, according to the present invention, in the manner shown in Figure 8, the part (a) of which illustrates the 60 mechanism employed and the part (b) the electrical diagram. The mechanism referred to comprises two condensers 120, 121, which may for example, be of the type having sliding armatures, in which case they have three sets of armatures. 65 The armatures of these condensers are controlled by cams 122, 123. The cams 122, 123 are keyed on to the shaft mechanically connecting the differential of the block N to which the condensers in question appertain, to the differential of the 70 block immediately above (N+1). Their profile is so chosen that the variation of frequency is in direct relation to the rotation of the shaft. The cams are reversed one with respect to the other in order to obtain the reversal of the law of variation. The operation in forward or in reverse di-

rection results, as shown by Figure 8b from the position of the switches 124, 124', 124'' appertaining respectively to the sets of armatures, these switches being connected by the section combiner.

3. Frequency of conversion

The value of the frequency utilised for the conversion is one or the other of two fixed values given by quartz oscillators, the frequency of which has or has not been multiplied.

In the present example, the carrying out of the range necessitates eight quartz oscillators, arranged two for each block and distributed according to the following table:

Table

No. of the block	II	III	IV	V
Frequency of 1st quartz oscillator	Kc. 500	Kc. 1,500	Kc. 4,500	Kc. 13,500
Frequency of 2d quartz oscillator	700	2,100	6,300	18,900

These different frequencies may be obtained from the two quartz oscillators of 500 and 700 kc. respectively by several times tripling the frequency: if need be, a single quartz oscillator of 100 kc. may be started with. The latter arrangement permits of the maximum of precision over the whole range.

Only block I uses the frequency of a continuous range heterodyne H of ratio 5:3 and the two beats of which are taken; it constitutes the high frequency part of the "normal receiver."

4. Combiner

Each block has a combiner which supplies:

- A relay which controls the aerial input and the high tension supply of the block;
- A relay which, according to the sense of variation necessary, connects one or the other of the variable condensers to the tuning self-induction of the block, according to the diagram of Figure 8b;
- A relay which gives the frequency necessary for the conversion, from the quartz oscillator or oscillators, and
- A servo-motor which adjusts the differential in operation (Figure 9).

As has been remarked with respect to the control of the variable condensers, the combiners of each block are controlled by a single manipulation by the section-changing handle which directly actuates the counter, in such a manner that the combiner allocated to a block of higher index changes three times less than the preceding combiner.

This condition is carried out, according to the present invention, by Maltese crosses of ratio 3 which are inserted between the controls of the combiners of the different blocks. Figure 10 shows the general operation of the combiners. The section handle 130 directly operates the spindle of the switches allocated to the block I. These switches are distributed in four series, shown diagrammatically in the form of four discs 131, 132, 133, 134 with three positions of contact. These discs insure respectively the four functions enumerated above under (a) to (d). Other discs may be provided, either to subdivide the operations or to insure supplementary operations allocated to each block. Through the intermediary of the Maltese cross connection 135, 136, the spindle of the switches of the block I drives the spindle of the switches of the block

II in such a manner that for one revolution of the first spindle, the second is shifted by a third of a revolution, and so on from one spindle to the next. The method of operation from the section handle of the counter drums has not been shown.

There may be used to this end, the embodiment described hereinbefore. There may also be used a servo-motor drive of the type used in the arrangement of Figure 9. The same type of control could, furthermore, be used in place of Maltese cross systems in the connections between the spindles of the switches of blocks I to V thus eliminating any motive effort to be supplied by the section handle 130.

16 The remainder of the receiver comprises (see Fig. 6) the usual elements of an amplifier, mean frequency filter MF on 50 kc., low frequency BF, and supply R.

What I claim is:

1. Apparatus for the interconversion of frequencies between two ranges thereof, one being an extended range including higher frequencies (F_1) and the other being a fraction of the first mentioned range and including lower frequencies (F_0), comprising oscillator means having a commutator, for the generation of at least two fixed frequencies (F_q), so chosen that there can be a transformation, by combination with one of the fixed frequencies with each frequency of one range, of each frequency of a range into a frequency of the other range, means including commutators for effecting tuning on each section corresponding to a portion of the range of higher frequencies, means including commutators for tuning on the range of lower frequencies, means for effecting coupling between the first mentioned and second mentioned tuning means and the commutator of said oscillator producing the said fixed frequencies, said coupling means being constructed and arranged so that the said higher and lower frequency ranges are each covered in its totality and in a continuous manner by one or more tuning devices variable linearly with frequency, said coupling between tuning devices for the lower and the higher frequencies comprising demultiplication means, whereby under control of the tuning devices the frequencies tuned in the higher and lower frequency ranges are changed by a like absolute value, and an adjusting means which on passing to another section of the range of the higher frequencies enables the adjustment by a predetermined amount of the tuning means for the higher frequency range relative to that of the lower range.

55 2. Apparatus according to claim 1 wherein the said adjusting means comprises a differential device having central planetary wheels and a cage carrying cooperating satellites, the said central planetary wheels being connected respectively to the tuning devices of the lower and higher frequency ranges and including means for effecting changeover to the different sections of high frequency range, said changeover means controlling said cage.

60 3. Apparatus according to claim 1 including a control device having a continuous movement for controlling simultaneously the tuning device of the lower and higher frequency ranges, a controlling device having a discontinuous movement and having a distinct position for each section of the high frequency range and comprising a number of levers, a drum with intermittent rotary movement for controlling the position of said levers, means by which one lever controls 70 the adjusting means, a second lever switches the

oscillator which produces the fixed frequencies, a third lever reverses the direction of variation of the tuning device of the lower frequency range with respect to those of the higher frequency range, and a fourth lever changes over the antenna.

4. Apparatus according to claim 3, including a further lever for locking the adjusting means when the said drum is at rest.
